PHONOGRAPH TONE ARM

Clarence L. Folden, Park Forest, Ill., assignor to
Sears, Roebuck and Co., Chicago, Ill., a corpora-
tion of New York

Application June 12, 1952, Serial No. 20,162

Term of patent 7 years

(Cl. D26—14)

To all whom it may concern:

Be it known that I, Clarence L. Folden, a citizen of the United States, residing in Park Forest, in the county of Cook and State of Illinois, have invented a new, original, and ornamental Design for a Phonograph Tone Arm, of which the following is a specification, reference being had to the accompanying drawings, forming a part hereof.

Fig. 1 is a perspective view of a phonograph tone arm embodying my new design.

Fig. 2 is a top plan view of the same.

Figs. 3 and 4 are elevational views of the respective sides of the tone arm.

Fig. 5 is a rear elevational view of the same, and

Fig. 6 is a front elevational view thereof.

The dominant features of my design reside in those portions shown in full lines.

I claim:

The ornamental design for a phonograph tone arm, as shown and described.

CLARENCE L. FOLDEN.
